UNITED STATES PATENT OFFICE

NICOLA C. PETRILLO, OF ST. LOUIS, MISSOURI

GLOBE OR SHADE HOLDER

Application filed May 31, 1929. Serial No. 367,173.

The object of my invention is to make a globe or shade holder to be used principally for large globes or shades, such as are used for street lights in cities. A further object is to make a globe or shade holder, which will prevent the breakage that now occurs in these globes or shades, which are made of glass or other fragile material. These globes are in most instances large and expensive. The breakage loss is very great in actual use. The globe or shade must be removed at regular intervals in order to clean the shade or globe and in order to replace burnt out electric light bulbs. The globes or shades are supported in supports, which in turn are secured to the top of posts. The actual securing means between the post and the globe or shade are screws, which pass through the support or base and come into frictional engagement with the globe or shade. The globe or shade must be held rigid in the base. This requires that the screws be drawn tightly against the globe or shade. In practice the screws although made of brass or other non-rusting material corrode, so that they may not be turned with the fingers. In this condition it requires a pair of pliers to turn the screws. When the pliers are used for this purpose, it is not possible to determine when the screws are sufficiently tight. One or two turns of any of the screws, after the screw is in positive contact with the shade or globe, will crack the lower flange of the globe or shade, after which the globe or shade must be replaced, because it is unsafe to use such a globe or shade having such a fracture. At the fracture, the globe subsequently breaks and the globe falls from its base. The specific purpose of my invention is to prevent the cracking of the lower flange of the globe or shade by introducing a split ring against which the tightening screws come in contact. By this means in the ordinary tightening of the screws, the flange of the globe or shade will not be broken. Furthermore by my construction the pressure on the globe at its lower flange is uniform over its entire periphery. This prevents the cracking of the globe due to unequalled strains to which the lower flange of the globe

is subjected when the screws come in direct contact with the globe or shade. Furthermore I have provided means for adjusting the length of the split ring to take care of the slight variation in the diameter of the lower flange of the globe or shield.

My device may be made of few and simple parts that lend themselves readily to multiple production.

With these and other objects in view my invention has relation to certain novel features of construction and arrangement of parts as will be hereinafter more fully described, pointed out in the claim and illustrated in the drawing, in which—

Fig. 1 is a fragmental front elevation of a globe or shield with my support therefor.

Fig. 2 is a sectional plan on the line 2—2 of Fig. 1.

Fig. 3 is a fragmental sectional elevation 70 on the line 3—3 of Fig. 2.

Fig. 4 is a plan view of the annular disc used in my device partly in section in its open position.

Fig. 5 is an enlarged fragmental plan of 75 the means of connecting the ends of the annular disc shown in Fig. 4.

Fig. 6 is a fragmental sectional elevation on the line 6—6 of Fig. 5.

Numeral 7 indicates the globe or shade. Numeral 8 indicates the base or support for the globe 7. The base or support 8 is annular in shape having the upper internal flange 9 and the outer wall 10 forming the annular recess 11. Numeral 12 designates an annular depending flange positioned below the annular recess 11. The base or support 8 is secured to a pole, not shown, by means of the annular depending flange 12. On the lower portion of the globe or shade 7 is formed the conventional annular flange 13, which rests in the annular recess 11. Radial tapped holes 14 are formed in the outer wall 10. In these holes are placed in threaded engagement the screws 15. In Fig. 2, four such screws are shown. Numeral 16 designates a split ring of substantially the same diameter on the annular flange 13. The split ring 16 is formed in two parts secured together by the hinge 17. Numeral 18 designates the lock generally 100

for selectively securing the free ends of the split ring 16 together. The lock 18 is formed as follows:

Numeral 19 designates a clasp in threaded engagement in one of the free ends of the split ring 16. By means of the threads on the clasp 19, it may be screwed in and out of the end of the split ring 16. Near the free end of the clasp 19 is formed the notch 20. In the other free end of the split ring 16 is secured spring 21, by means of the rivet 22. The free end of the spring 21 is bent at right angles inwardly into the slot 23 formed in the split ring 16. The spring 21 is normally in the position shown in Fig. 6, that is in engagement in the notch 20 in the clasp 19. Numeral 24 designates a cylindrical hole formed in the end and extending circumferentially in the split ring 16. It will be seen that when the clasp 19 is screwed, so that the notch 20 faces outwardly and the clasp 19 is inserted in the cylindrical hole 24, that the ends of the split ring 16 will be locked together by reason of the notch 20 becoming engaged with the free end of the spring 21. In order to disengage the free ends of the split ring 16, it becomes necessary to press the spring 21 outwardly out of engagement with the notch 20. In order to facilitate this operation the slot 25 is provided.

When the split ring 16 is placed in the annular flange 13 of the globe 7 as shown in Fig. 3, the screws 15 are tightened into the external circumferential slot 26 formed in the split ring 16. By this means there is no contact between the screws 15 and the annular flange 13, the contact being between the split ring 16 and the annular flange 13.

What I claim and mean to secure by Letters Patent is:

A split ring hingedly secured together at two of its free ends and having a locking device secured at its other two free ends, said locking device comprising a spring secured to said split ring and having its free end normally penetrating into a slot in said split ring, a circumferential cylindrical hole formed in the same end of the split ring in communication with the slot formed in said split ring, a clasp in threaded engagement in the other free end of said split ring, said clasp having a notch formed at its free end for passage into the cylindrical hole in the other free end of said split ring and for selective engagement with the free end of said spring.

In testimony whereof I affix my signature.
NICOLA C. PETRILLO.
